CARL JOHAN JACKSON, OF SUPERIOR, WISCONSIN.

SCREEN ATTACHMENT FOR WINDOWS.

Specification of Letters Patent. Patented July 17, 1917.

1,234,034.

Application filed October 4, 1916. Serial No. 123,744.

To all whom it may concern:

Be it known that I, CARL J. JACKSON, a citizen of the United States, residing at Superior, in the county of Douglas and State 5 of Wisconsin, have invented a new and useful Screen Attachment for Windows, of which the following is a specification.

This invention relates to screen attachments for windows.

10 The object is to improve the construction of the screen attachment shown and described in Patent No. 1,117,390, issued to me November 17, 1914, and to provide improved means for permitting and directing the exit 15 of flies from the interior of a room, at the same time preventing the entrance of flies while the upper sash of the window is in a lowered position for ventilating the room.

A further object is to simplify the construction of the device by the elimination 20 of some of the stamped metallic parts shown in said patent, thus rendering it possible to construct the attachment with a minimum number of parts, and at a much reduced cost, 25 and to provide a device which may be readily applied to a window of ordinary construction by an inexperienced person.

A full and complete understanding of the 30 invention may be obtained from a consideration of the following detailed description, taken in connection with the accompanying drawing forming a part of this specification; it being understood that while the drawing shows a practical form of the invention, the 35 latter is not confined to strict conformity therewith, but may be changed or modified so long as such changes or modifications mark no material departure from the salient features of the invention, as specifically 40 pointed out in the claims appended hereto.

In the drawing, in which like reference characters designate similar parts throughout the several figures:—

Figure 1 is an elevation partly broken 45 away, of a window and frame of ordinary construction as viewed from the inside, and having my improved device applied thereto.

Fig. 2 is a similar view, as seen from the outside.

50 Fig. 3 is an enlarged detail vertical sec-

tion through the upper sash, and adjacent parts, showing the said sash in elevated position.

Fig. 4 is a similar view, with the upper sash in lowered position. 55

Fig. 5 is a detail vertical section on the line 5—5 of Fig. 1.

In the drawing there is shown a window frame or casing 1, of ordinary construction, provided, in the usual way, with a dividing 60 bead or strip 2 and inner and outer beads or strips 3 and 4, thus producing the necessary channels 5 and 6 for the upper and lower sashes 7 and 8, respectively. As thus far described, the parts may be all of the ordinary construction with the exception that it has been found advantageous with the use 65 of the present device to remove the upper cross bar of the upper sash in order to expose the upper edge of the glass for a purpose to be described. This, however, is not obligatory, as the device may be used successfully with the said cross bar remaining 70 in place.

A section of wire gauze 9 or other screen 75 material is secured to the inner faces of the dividing beads or strips 2, said section 9 extending entirely across the upper portion of the window opening and being of a width sufficient to extend downwardly a 80 distance great enough to permit the lowering of the upper sash a considerable distance for ventilating purposes, and still extend below the upper edge of the glass in 85 the upper sash.

Fastening means such as screws 10 are preferably employed to secure the screen to the dividing beads 2, washers 11 being interposed to receive the heads of the fastening devices so that the screen may not become dislodged therefrom. Binding strips 12, of thin metal are arranged at the ends 90 of the strip of wire gauze and against the inner faces of the vertical portions of the dividing beads 2, the upper ends of said metallic strips 12 being secured to the beads 2 by the upper fastening means 10. The lower ends of the strips 12 each have a return bend 13 to be engaged by the lower 95 fastening means 10. Thus, the heads of 100

the various screws 10 are covered by the strips 12. A horizontally disposed flat metallic strip 14 is placed across the top of the wire gauze 9 and is secured, adjacent to its ends, by screws 15 or other fastening means. It will thus be seen that the wire gauze screen 9 is permanently fixed within the window frame and at a point sufficiently above the top of the lower sash to permit 10 of raising the same sufficiently for ordinary purposes. Stops 16, composed of angular metallic plates having inwardly directed portions 17 are secured within the channel 6 on opposite sides in order to prevent the 15 top bar of the lower sash from striking the bottom of the screen 9.

A relatively narrow strip of wire gauze 18 similar to that forming the screen 9 is suitably hinged as at 19 to the outer face of 20 the screen 9 at a point slightly below the horizontal center line thereof and is adapted to extend across the path of movement 25 of the upper sash 7 and to normally lie and be supported in an inclined position by stop pins 20, as clearly illustrated in Fig. 4, when the upper sash is in its lowered position for ventilating the room and permitting the exit of flies or other insects therefrom. When the parts are in the position 30 shown in Fig. 4, the strip 18 is supported by the pins 20 in spaced relation to the upper edge of the glass, thus providing a space 21 sufficient for the exit of the flies which crawl upwardly on the inner face of the 35 glass over the top edge thereof and are then free to escape.

In practice, the lower sash is ordinarily shaded or screened, so that the light through 40 the upper sash will attract the insects and cause the same to pass out through the exit 45 passage 21.

As shown in Fig. 3 of the drawings, the upward movement of the upper sash will cause the strip 18 to swing on its hinges 19 and assume an upwardly inclined position with the free edge thereof resting against the inner face of the upper sash 7, thus offering no interference with the free movement of said sash. In the present instance, 50 the strip 18 is shown hinged to the screen 9 by small wire loops, though it is to be understood that any other hinging means which will permit of the free swinging movement of the strip 18 may be employed. 55 Ordinary spring-pressed bolts 22 are carried by the upper sash and are adapted to engage the window frame or casing 1 in order to hold the upper sash in any desired adjustment. These bolts are arranged a sufficient distance above the bottom of the 60 upper sash, so as to be exposed for operation above the lower sash when the said upper sash is in its lowermost position. Any other suitable locking means may, however, be

employed for securing the upper sash in its 65 adjustment.

Stops 23 similar to the stops 17 are located within the channels 5 sufficiently below the upper sash 7 to arrest its movement, upon being lowered, and support the sash in 70 a position with the upper edge of the glass thereof in proper relation to the outwardly inclined strip 18.

From the foregoing it will be seen that the more or less expensive structure shown 75 in the aforementioned patent has been greatly simplified by dispensing with the metallic guide members carried by the screen frame, and in which are adapted to travel certain other members carried by the 80 upper sash in its vertical movement within the window frame or casing, thus resulting in a material reduction in the cost of manufacture:

What is claimed is:—

1. A window screen attachment including 85 a screen adapted to be secured within the upper portion of a window frame, a horizontally disposed strip hingedly connected along one long edge to the outer face of the 90 screen on a horizontal line, stops for supporting the said strip in an outwardly and downwardly inclined position over the upper edge of the upper sash, when the latter is in a lowered position, and stops for supporting the said sash in spaced relation at 95 its top to the strip in order to form a fly exit.

2. A window screen attachment including 100 a strip of wire gauze to form a screen 100 permanently fixed within the upper portion of a window frame or casing, a relatively narrow wire gauze strip hinged horizontally along one edge to the middle portion of the screen and of a length approximately equal 105 to the distance between the opposite dividing beads or strips of the frame and adapted to be swung by the upper sash when the same is closed into an upwardly inclined position between the said sash and the screen, 110 and stops provided on the opposite faces of the dividing beads and in the path of movement of the hinged strip to support the latter in a downwardly and outwardly inclined 115 position over the top of the upper sash and in 120 spaced relation thereto when the said upper sash is in its lowered position, stops located in the upper sash channels for supporting the sash in said position and stops located in the lower sash channels for limiting 125 the upward movement thereof.

3. A window screen attachment including 130 a strip of wire gauze to form a screen permanently fixed within the upper portion of a window frame or casing above the lower sash, a wire gauze strip hinged horizontally along one edge to said screen and extending outwardly so as to extend beyond the

path of movement of the upper sash, said strip being swung upwardly by the upper sash when the latter is closed and fitting between the screen and the upper sash, and
5 means for supporting the strip in an outwardly extending position in spaced relation to the top sash so as to form a fly exit.

In testimony that I claim the foregoing as my own, I have hereto affixed my signature in the presence of two witnesses.

CARL JOHAN JACKSON.
